SERVICE APPARATUS

Filed Sept. 5, 1924

UNITED STATES PATENT OFFICE.

FLOYD E. ADAMS, OF PONCA, NEBRASKA.

SERVICE APPARATUS.

Application filed September 5, 1924. Serial No. 736,139.

This invention relates to a service apparatus designed for the convenience of motorists.

An object of the invention is to provide an air and water tower of a simple, cheap and durable construction.

Another object of the invention is to provide a water tower in which water is automatically drained to prevent freezing.

Another object of the invention is to provide swinging air and water hoses to be convenient for use with an automobile and at the same time position the hoses so that they will not be in contact with the ground, thereby preventing damaging of the hoses by automobiles running over the same.

Other objects and advantages will appear from the following description, taken in connection with the accompanying drawing, wherein

Figure 1 is a vertical sectional view of the tower and base;

Fig. 2 is a fragmentary vertical section showing the top of the tower and air hose, the hose being in operation; and,

Fig. 3 is a vertical sectional view of the water valve, on an enlarged scale.

In the drawings, wherein the same part is characterized by the same numeral, part 4 is a cylindrical water tower secured to a base 5 by suitable connecting means 6. The tower is open at the top, as shown at 7, though obviously it could be partially closed to prevent rain or snow entering the same and interfering with the proper operation of the device. Extending through the tower is an air line 8 and a water line 9. One end of the air line goes to a reservoir of compressed air (not shown). One end of the water line 9 is connected with a supply of water. The other end of the air line 8 goes to an air chuck 10 of the conventional type. The other end of the water line 9, at 11, is used to permit the filling of an automobile radiator.

In use, the air line is swung down in position, as shown in Fig. 2. To the top of the water tower or column 4, a bracket 12 is connected. Pivots connected to the same is a swinging member 13, having suitable collars 14, surrounding the air line 8. Also attached to the pipe is another collar 15, carrying a rod 16, which is connected with a retractile spring 17, attached to hook 18.

After the air pipe or hose 8 is swung to operative position, shown in Fig. 2, the pipe

is swung back to the position, shown in Fig. 1, by means of the retractile spring 17. Obviously the tension of spring 17 may be properly adjusted at any time by means of suitable nuts, as shown.

A substantially similar hinge construction is applied to water tube 9. This construction has a bracket 19 connected to tower 4 and hinged thereto a co-acting member 20. This is connected to a metal pipe 21, which is a part of the water line 9, by any suitable means, such as a collar 22.

When a pull is made on the water tube 9, at port 11, the water tube will swing to an outward position, in the same manner that the air tube would swing, as shown in Fig. 2. When this water tube swings out, water will issue through port 11, to a vehicle radiator. When the water tube is swung back to normal position, no more water will issue from port 11. This is accomplished by the following mechanism:

To the water tube 9 there is attached a collar 23, connected with a rod 24, which is attached to a hook 25, this hook being adjustable through nuts 26. At right angles to the longitudinal axis of the hook 25, an arm 27 is connected to a valve stem 28. Around the valve stem is a spring 29 and at the lower end is the valve 30, clearly shown in Fig. 3. This construction operates as follows:

Upon a pull on the water line 9, say at 11, rod 24 will be pulled upward, lifting hook 25, arm 27, valve stem 28 and valve 30. Water will then pass from pipe 31 into valve proper 32, elbow 33 and up through the tube 9 and issue at port 11. When the hand is released from the water tube, it will swing back to the position, shown in Fig. 1 and in this way rod 24 will drop and the valve 30 will close.

Water, which remains in the water line, will run out through a port 34 or from the end of the water line, at 11. In this manner, water will not remain standing from the water valve to the end of the line 11, consequently freezing cannot take place. It is, therefore, obvious that in freezing climates, this water tower may be used the year around, without danger of bursting pipes.

Not only does the construction illustrated show a convenient means of suspending an air and water hose and a mechanism to prevent damage due to freezing temperatures, but it also places the air and water hoses at a convenient position for motorists. Furthermore, as the hoses do not touch the

ground, they cannot become greasy or dirty nor can they be stepped upon or get under the wheels of automobiles.

It is to be understood that the form of my invention, herein shown and described is to be taken as a preferred example of the same, and that various changes in the shape, size and arrangement of parts may be resorted to without departing from the spirit of the invention or the scope of the subjoined claim.

Having thus described my invention, what I claim as new and desire to secure and protect by Letters Patent of the United States is:

15 An apparatus of the character described comprising a water line having a vertically disposed portion extending from a point be-

low the surface of the ground to an elevated point and having at its lowermost end a relatively small discharge orifice for draining said vertical portion, said vertical portion having its upper portion in the form of a rigid tube pivotally mounted to swing in a vertical plane, said water line also having a freely movable portion depending from the upper end of said rigid tube and having at its free end a discharge port, a manually operable valve in the water line, a collar on said rigid tube, a rod attached to said collar, hook means connected to said rod and to the water valve whereby when the free end of said depending portion is pulled said rigid tube will be pivoted to actuate said valve.

FLOYD E. ADAMS.
